UNITED STATES PATENT OFFICE.

CONSTANTIN KRAUSS, OF COLOGNE-BRAUNSFEILD, AND PAUL STÄHELIN, OF KNAPSACK, NEAR COLOGNE, GERMANY.

APPARATUS FOR THE PRODUCTION OF NITROGEN COMPOUNDS.

1,211,181.

Specification of Letters Patent.

Patented Jan. 2, 1917.

Original application filed December 6, 1913, Serial No. 805,180. Divided and this application filed March 26, 1915. Serial No. 17,286.

To all whom it may concern:

Be it known that we, CONSTANTIN KRAUSS and PAUL STÄHELIN, subjects of the King of Prussia, German Emperor, residing at 5 (1) Cologne-Braunsfeld and (2) Knapsack, near Cologne, Germany, have invented certain new and useful Improvements in Apparatus for the Production of Nitrogen Compounds, of which the following is a 10 specification, reference being had therein to the accompanying drawing.

This invention relates to an apparatus for the production of nitrogen compounds, more especially for the execution of the 15 process described in our application No. 805180, filed Dec. 6, 1913, the present application being a divisional application thereof. The said process consists essentially in passing the metal carbid through 20 a preheating space, a heating space, and a reduction space and then passing the metal carbid through a cooling space.

The accompanying drawing shows a simple apparatus for carrying out this process, 25 in which—

Figure 1 shows a longitudinal section of a channel furnace. Fig. 2 shows a modification of the apparatus shown in Fig. 1, and Fig. 3 is a plan view on the line $x-x$ 30 of Fig. 2.

For the first mode of working described in our specification 805180, there is employed a horizontal channel furnace (Fig. 1). This furnace consists of four parts: 35 1, a preliminary heating space; 2, a full heating space; 3, a reaction space, and 4, a cooling space.

In the preliminary heating zone or space V the reaction product (finely pulverized 40 carbid or carbid mixtures with or without additions which facilitate the reaction) is warmed by means of the gases escaping from the other spaces. In the heating zone H, the carbid is heated up to the temperature 45 necessary for the carrying out of the reaction. In the reaction zone or space R the treatment with nitrogen is effected; in the cooling space K, the finished product is cooled down until it can be withdrawn 50 without special precautions and can be further utilized.

The method of working is as follows:— The finely pulverized material, to which

substances facilitating the reaction can be added, is transported by mechanical means, 55 such as tracks, transporting bands or the like through the furnaces. In the contrary direction to that in which the material to be treated with nitrogen is transported, there is admitted cold nitrogen gas. 60 In the preliminary heating space the escaping gases give up part of their heat to the material and are drawn off comparatively cool. The material then passes somewhat warmed into the heating space, where it is 65 heated up to the reaction temperature, either by means of an electric heating device or by outside fire. The consumption of heat energy is thus very small, because the nitrogen gas coming from the cooling and reaction spaces 70 is already so hot, that it reacts upon the material to be nitrogenized, causing further reaction heat to be liberated which again supports the reaction. The heating space serves therefore properly only as a 75 heat regulator.

From the heating space, the reaction mass passes into the reaction space. There is here a space between the cool inflowing nitrogen gas and the reaction masses proceeding out of the heating space of such a kind that under all circumstances, the reaction mass before cooling must exceed the critical temperature which assures the quantitative nitrogenizing and prevents 80 any reformation of the carbid. As above stated, it is necessary to work with a quite 85 extraordinarily great surplus of cold nitrogen in order to overcome by this means the degrees of heat liberated. This would, 90 however, render the process very costly and moreover enable no certain working reaction because under certain circumstances, during short interruptions of the operation, local heating can take place which 95 might injure the material in the furnace or the transporting mechanism. We have therefore in addition to the regulatable internal supply of the cool nitrogen current, also devised a regulation of the furnace by 100 outward cooling. For this purpose, we have surrounded the channel furnace with an outer cooling mantle and have constructed the inner mantle from material which conducts heat. By this arrangement 105 it becomes possible whenever the various

measuring instruments inserted in the reaction space indicate an undesirable rise of temperature, to act immediately upon the temperature by passing cold air between the channel furnace and the mantle. In this manner therefore, a double temperature regulation takes place, firstly by the nitrogen in the interior of the channel furnace and secondly by air and cooling gases at the outside. As the overheating (as already stated) is chiefly local, we have arranged to allow the cold nitrogen gas to flow into the reaction space at various points to regulate temperatures. Moreover, we have divided the cooling space between the channel furnace and the outer mantle in various divisions, as may be seen in the drawing, whereby we are in the position to cool certain parts of the channel furnace according to requirement.

From the reaction space the reacting material passes into the cooling space and is also capable of being cooled down by surrounding air so that the reaction mass can be so far cooled that its removal from the furnace and its further treatment is not hindered.

For the second method of working described in our application 805180 in which the material absorbing the nitrogen is not moved but remains at the same position in the furnace until it is completely used up, a kind of ring furnace (Figs. 2 and 3) is provided, the operation of which is as follows:

In the various chambers or zones of the furnace (Figs. 2 and 3) the carbid or the carbid mixture is spread out on stages in layers. The separate chambers R, R are provided with suitable heating devices H for electric internal heating. The nitrogen enters at various points in the separate chambers. For the commencement of the process, there is first heated one chamber or zone to the reaction temperature, then cooled nitrogen is passed in and in such a quantity that the same suffices to prevent the reaction temperature rising beyond the best point. For this there are obviously required much greater quantities of gas than are needed for the saturation of the carbid which is in the chamber. The unconsumed highly heated nitrogen is introduced in the second chamber and reacts upon the carbids there. Here again, reaction heat is liberated which would lead to the overheating of the reaction product. In order to prevent this cooled nitrogen is introduced in such quantities that the best reaction temperature is not exceeded. The nitrogen is passed through the first chamber until the mass is sufficiently cooled. This hot nitrogen passes as already stated, from the first into the second chamber. The temperature of the nitrogen passing in is lowered but in the degree that the reaction product is added in the chamber, conse-

quently the introduction of fresh cold nitrogen in the second chamber must be gradually reduced.

The same operation takes place in the third chamber again and so forth. The heating of the chambers will therefore only need to be undertaken when for some reason, a chamber has not attained to the necessary reaction temperature or when a furnace is being newly started. As even in this mode of working, local overheatings are not impossible, we have constructed in the separate reaction chambers cooling tubes or cooling boxes K of material which easily conducts heat, through which cold air can be passed, as soon as the measuring instruments indicate an undesirable rise of temperature.

It will be obvious without further explanation that firstly a choking of such apparatuses is rendered impossible, whereby a uniform action of the nitrogen is secured, and that secondly, an injurious overheating of the reaction product and a decomposition of the nitrogen compound already formed is rendered impossible, because in the attaining of the most suitable reaction temperature, no overheating but rather a gradual cooling takes place in the nitrogen current, and because moreover the reaction product leaves the apparatus cooled. According to our process there arises in the action of nitrogen on carbid a mixture of nitrogen compounds, chiefly calcium cyanamid, and also dicyandiamid and cyanamid. By proper additions we are in a position to increase the production of one of the latter products at the expense of the cyanamid. Finally the saving of heat is the most favorable possible because both the heat which is in the product left in the furnace is absorbed by the incoming current of cold nitrogen gas and also the heat of the nitrogen gas which is drawn off is continuously transferred to the newly charged reaction mass, and also the reaction heat liberated during the reaction is so controlled that it co-operates to assist and not to injure the process. Saving of heat according to our process is actually so favorable that the reaction proceeds almost entirely without the addition of heat from without when once the mass in the furnace has been brought to the requisite temperature. The heating devices then serve simply as regulators of the temperature.

Having now particularly described and ascertained the nature of our said invention and in what manner the same is to be performed, we declare that what we claim is:

1. An apparatus for the continuous production of nitrogen compounds from metal carbids and nitrogen, comprising an elongated furnace, means for transporting the metal carbids through said furnace in one direction, means for introducing nitrogen

120

through said furnace in a direction opposed to the travel of said transporting means, and means for cooling the major portion of said furnace.

5. 2. An apparatus for the continuous production of nitrogen compounds from metal carbids and nitrogen, comprising an elongated furnace, means for transporting the metal carbids through said furnace in one direction, means for introducing nitrogen through said furnace in a direction opposed to the travel of said transporting means, means for regulating the supply of said nitrogen, and means for cooling the major portion of said furnace.

20. 3. An apparatus for the continuous production of nitrogen compounds from metal carbids and nitrogen, comprising an elongated furnace, means for transporting the metal carbids through said furnace in one direction, means for introducing nitrogen through said furnace in a direction opposed to the travel of said transporting means, independent means for successively regulating 25 the supply of said nitrogen, and means for cooling the major portion of said furnace.

30. 4. An apparatus for the continuous production of nitrogen compounds from metal carbids and nitrogen, comprising a furnace arranged to provide a plurality of zones, means for transporting the metal carbids progressively through said zones in one direction, means for introducing nitrogen through said zones in a direction opposed to 35 the travel of said transporting means, means for regulating the supply of said nitrogen, and means for cooling the major portion of said furnace.

45. 5. An apparatus for the continuous production of nitrogen compounds from metal carbids and nitrogen, comprising a furnace arranged to provide a preheating zone, a main heating zone, a reaction zone and a cooling zone, means for transporting the metal carbids progressively through said

zones, means for introducing nitrogen through said zones in a direction opposed to the travel of said transporting means, means for regulating the supply of said nitrogen, and means for cooling the major portion of said furnace.

6. An apparatus for the continuous production of nitrogen compounds from metal carbids and nitrogen, comprising a furnace arranged to provide an inner section and an outer section, said furnace having a preheating zone, a main heating zone, a reaction zone and a cooling zone, means for transporting the metal carbids through said inner section in one direction, means for introducing nitrogen through said inner section in a direction opposed to that of the travel of said transporting means, and means opening through said outer section for introducing a cooling medium to the major portion of 60 said inner section.

7. An apparatus for the continuous production of nitrogen compounds from metal carbids and nitrogen, comprising a furnace arranged to provide an inner section and an outer section, said furnace having a preheating zone, a main heating zone, a reaction zone and a cooling zone, means for transporting the metal carbids through said inner section in one direction, means for introducing nitrogen through said inner section in a direction opposed to the travel of said transporting means, means for regulating the supply of said nitrogen, a plurality of cooling chambers formed interiorly of 70 said outer section and surrounding said inner section, and means for introducing a cooling medium to said chambers.

In testimony whereof we affix our signatures in the presence of two witnesses.
